Marie Platt, INVENTOR:

BY
Medusiney Fairbanks
ATTORNEYS.

This invention is especially concerned with the cutting and dividing of pearl stock, whether such stock be natural and uncut, or cut and polished, for the purpose of producing button blanks of uniform thickness and parallel faces.

It is an object of the present invention to provide a novel apparatus for cutting parallel faced button blanks from pearl stock, and producing, moreover, button blanks of a relatively small thickness and varying the thickness of such blanks at will.

UNITED STATES PATENT OFFICE

MAURICE PLATT, OF CAMDEN, NEW JERSEY, ASSIGNOR TO PEERLESS PEARL COMPANY, OF CAMDEN, NEW JERSEY, A CORPORATION OF NEW JERSEY

METHOD AND APPARATUS FOR MAKING BUTTON BLANKS

Application filed November 26, 1926. Serial No. 150,694.

This invention has relation to a new and useful method and apparatus for cutting or dividing pearl stock into blanks or discs, and it relates more particularly to the novel manner and apparatus for automatically and economically producing button blanks from pearl stock or mother of pearl, for the manufacture of buttons and the like.

This invention further relates to a novel apparatus whereby a large number of button blanks may be produced simultaneously and whereby the uniform thickness of such blanks may be accurately gauged and predetermined.

This invention still further relates to a novel apparatus whereby button blanks may be produced, having their opposed faces parallel to each other and perpendicular to the periphery thereof, and of a thickness closely approximating the desired thickness of the finished button, thus greatly reducing the work and time otherwise consumed in the finishing and backing operations and thereby effecting a great saving in time, labor, and material.

The leading object of the present invention may be said to reside in the provision of a new and novel method of blank formation which may be practiced more efficiently and more economically than heretofore accomplished.

A further object of the present invention resides in the provision of new, novel and appreciably simplified mechanism for attaining the efficiency and economy above referred to.

Other and further objects of the present invention reside in the provision of the novel arrangement, construction, and combination of parts for attaining the results sought in the foregoing objects.

Another object of the present invention is to provide novel apparatus for severing pearl stock into button blanks, whereby a great number of such pearl stock is firmly gripped in position with respect to a plurality of regulated, automatic cutting means, thus producing a plurality of such blanks in one operation and at minimum cost.

Another object of the present invention is

to provide novel apparatus for cutting parallel faced button blanks from pearl stock, and producing, moreover, button blanks of a relatively small thickness and varying the thickness of such blanks at will.

Other and further objects of the present invention will be more apparent from the following description and the accompanying drawings, forming part hereof, and in which

Figure 1 represents a view in side elevation of apparatus for cutting pearl stock, embodying the invention.

Figure 2 represents a top or plan view of the same.

Figure 2a represents a perspective view of the chuck holder in detached position.

Figure 3 represents an end view looking towards the left hand side of Figure 1.

Figure 4, represents an end view of the right hand side of Figure 1.

Figure 5, represents a vertical sectional view taken upon the line 5—5 of Figure 2, certain of the parts being shown in elevation.

Figure 6, represents a view in side elevation of the shaft actuating the cutters and the chuck holder, the gears and bearings therefor being shown in section.

Figure 7, represents a sectional view taken upon the line 7—7 of Figure 2, and showing, upon an enlarged scale, the chuck holder seen in section in the top part of Figure 5.

Figure 7a, represents a perspective view of the cam shaft around which the chuck holder revolves.

Figure 8, represents a view in elevation hereinafter referred to.

Figure 9, represents a top or plan view of Figure 8.

Figure 10, represents a vertical sectional view of the upper portion of the chuck and its jaws.

Figure 11, represents a perspective view of one of the chuck jaws seen in Figures 7, 8, 9, and 10, in detached position.

Figure 12, represents a perspective view of a piece of the pearl stock to be severed.

Having now generally stated the nature and objects of the present invention, it may be proper to at this time state that the pres-

100

ent invention, generally and broadly stated, comprises a housing, suitably anchored to a stationary base, a plurality of power driven cutters carried by a laterally movable slide on said housing, means for accurately adjusting said cutting means with respect to the pearl stock to be cut, means for spacing said cutters with respect to each other to determine the thickness of the blanks to be produced, means for shielding said cutters, a plurality of power driven rotary gripping elements mounted on said housing in fixed operative relation to said cutters, and adapted to grip the pearl stock while the same is being cut, and means intermediate said cutters and said pearl stock for accurately aligning said cutters during the cutting operations. Other elements of my novel apparatus will be described more in detail in the following description taken in connection with the accompanying drawings:

Referring to the drawings, in which like reference characters indicate like parts, 1 designates my novel apparatus for severing pearl stock into button blanks, the same comprising a hollow, tapering standard or housing 2, supported upon the flat base 3, the standard being provided with the upper flange 4 upon which the upper portion of the apparatus proper is bolted or otherwise secured. The reference numeral 5 designates the main driving shaft to which power is applied by the tight pulley 6, the pulley 7 being loose, power being transmitted from said main shaft 5 to the shaft 8 by belt 9, which latter passes around the pulleys 10 and 11. The shaft 8 is mounted in the pendant bearings or brackets 12 and 13 and carries the pinion 14, meshing with gear wheel 15, which latter is loose on the shaft 16, as is the pinion 17, which is integral with or fastened to the gear 15. The pinion 17 meshes with the gear wheel 18, the latter being mounted on shaft 19 which shaft carries the pinion 20 which in turn meshes with gear wheel 21 fastened on shaft 16. Shaft 16 is mounted in the bearings 19a, 20a, and 21a, which is apparent from an inspection of Figs. 5 and 6, and at its right hand end carries the cam member 22 which is provided with a cam groove 23, whose inner walls engage the roller 24 carried on the pin 25, which roller is secured to the slide 26, which latter slides in the ways 27, as will be understood from an inspection of Fig. 4. The upper slide 28, mounted on the slide 26, (see Fig. 4), carries the shaft 29 having the pulley 30 to which power is applied by a separate belt 31 shown in dotted lines in Fig. 1. On the shaft 29 I mount the cutters 32, arranged in groups of four each, the blades in each group being separated from each other by thin washers 33, while the adjacent groups of cutters are separated by the thicker washers 34, as will be understood from Figure 2.

In practice six groups of cutters are employed, four cutters or blades to a group, as will be understood from Figure 2, the number of such groups of cutters or blades in each group being increased or diminished at will. The cutters 32 are preferably of thin, carborundum discs and they are protected by the guard 35, as will be understood from Fig. 5. As it is essential that provision be made for the adjusting position of the cutters 32 with great accuracy with respect to the pearl stock to be cut, I preferably provide an adjusting screw 36 having at its outer end the hand wheel 37. The adjustment screw is loosely mounted in the lug 38 carried by the slide 26 and the threaded portion thereof engages the externally threaded lug 39 which is carried by the slide member 28. Thus, when the hand wheel 37, and therefore the threaded screw 36, is rotated, the slide 28 and the shaft 29, and therefore the cutter 32 carried thereby, are moved towards or away from the pearl stock to be cut, thus effecting a very fine and accurate adjustment of the distance between said cutters and pearl stock to be cut. The reference numeral 40 designates a vertically disposed slotted guide plate through which plate the carborundum discs or cutters 32 project, whereby the latter are more accurately aligned as they move inwardly towards the pearl stock to be severed.

Referring now specifically to Figures 1 and 2, it will be seen that the loose gear 15 previously referred to is in mesh with the pinion 41 carried by the shaft 42 which is mounted in suitable bearings and which has on its inner end the worm 43 which engages the underside of the pinion 44. On the inner end of the shaft 45 is fixed the disc 46 which carries the roller 47 which engages the radially disposed slots 48 in the disc 49, the construction of which will be understood from Figures 1 and 2a. 49 designates the chuck holder and its adjuncts hereinafter described, which revolves freely about the stationary shaft 50, the outer ends of which are cylindrical and the intermediate portion of which is eccentric or cam shaped, as indicated at 51, as will be seen from Fig. 7a. The cylindrical ends of the stationary shaft 50 are mounted in suitable bearings 52, one of which is shown in Fig. 1. Still referring to Figs. 1 and 2, the generally cylindrical chuck holder 49 carries the chucks 55 arranged thereon in longitudinal, horizontal rows, parallel to each other and perpendicular to the periphery of said disc. In the preferred embodiment of my invention, shown particularly in Figs. 2a, 5, and 7, I employ four such rows of chucks 55 disposed at right angles to each other, said chuck holder 49 and its adjuncts, being adapted to revolve as a unit about the stationary, elliptical cam shaft 50, in a manner hereinafter described. Each chuck 55, partly enclosed in the frame 61, comprises the chuck

stem 62, the solid inner end of which passes through the block or bearing 64, and bears against the stationary shaft 50, while the body portion of said stem is split to form the 5 prongs 65 (see Figs. 7 and 10). The stem 62 is held in position, within the housing 61, by the coil spring 66, the inner end of which is secured thereto, by the threaded nut 67, while the outer end of said spring 66, 10 bears against the inner surface of the flange of closure 68 on the outer end of said housing 61. The prongs 65 outwardly flare near the outer extremity thereof to form the inwardly tapering portions 69, which are 15 adapted to tightly seat in the wedge opening 70, in the flange or closure 68 of said housing 61 when the stem 62 is urged inwardly by the force of the coil spring 66, on said stem 62, as will be described more in detail herein- 20 after. The tapering portions 69 terminate in the blocks or heads 71, in each of which is adapted to be rigidly and detachably secured a jaw member 72, by means of the screw 74, passing through the base portion 73, of said 25 jaw 72, on which is arranged the inwardly curved or concave row of teeth 76 (see Fig. 11) spaced from each other a suitable distance, as at 77. The chuck holder 49 carrying the rows of chucks 55, is revolved around the station- 30 ary shaft 51 by means of the roller 47, which engages the radial slots 48 in the outer face of said chuck holder 49. The roller 47 in turn is carried by the disc 46, which is fast on the shaft 45 and which is revolved in a 35 counter clockwise direction by means of the pinion 44 in mesh with the worm gear 43 on the shaft 42, which in turn is revolved or actuated by the pinion 41 which meshes with the loose gear wheel 15 on the shaft 16, said 40 shaft 16 being supplied with power by the belt 9 in the manner already described.

In carrying out my invention, I place pearl stock 78 on the board or feed table 78', from which pearl stock 78 is fed to the jaws 72 of 45 a chuck 55, when said chuck is in the vertical position indicated by "A" in Fig. 7. In this position a chuck 55 is in its outermost position, since the inner end 63 of the chuck stem 62 bears against the raised or cylindrical sur- 50 face of the shaft 50, thus forcing the portions 69 out from the said opening 70 against the force of the coil spring 66 and thus maintaining the jaws 72 on the outermost extremity of said chuck 55 in open or nongripping 55 position, thus facilitating the feeding thereto of pearl stock to be severed, as will be understood from Fig. 7. When the chuck holder 49, carrying the chucks 55, is revolved in a clockwise direction by the action of the roller 47, engaging the radial slot 48 in the face thereof, the inner end 63 of the chuck stem 62, leaves the raised or cylindrical surface of the shaft 50 and enters upon the low surface 51 of said cam shaft 50, the chuck 55 at the 60 same time traveling from the vertical posi- 55 tion A to the horizontal position B. As the inner end 63 of the stem 62 rides upon the cam surface 51 of the cam shaft 50, the coil spring 66 gradually urges a chuck 55 inwardly and gradually forces the flared portion 69 thereof into the wedge shaped opening 70 (see Fig. 7) thus bringing the jaws 72 firmly together and closing the same on the pearl stock 78. When the chuck 55 reaches the horizontal position B, in which the pearl stock is to be cut by the cutters 32, the inner end 63 of a chuck stem 62 bears against the lowermost part of the cam surface 51 of the shaft 50, and the spring 66 thereupon urges the chuck 55 inwardly until the flared portions 69 of said stem are very tightly wedged in the opening 70 thus further strengthening the grip of said jaws 72 on the pearl stock 78 clamped therein. In this horizontal position B of a chuck 55 in which the pearl stock 78 is firmly gripped by the jaws 72, the cutters 32 are moved forward into cutting engagement with the pearl stock 78, by the action of the roller 24, cooperating with the cam groove 23 and actuated by the shaft 16 in timed relation to the rotation of a chuck 55 around the shaft 50 and in timed relation to the rotation of the disc 46, in the manner already described. Thus, the width of the cam groove 23 is slightly greater than 65 the diameter of the pearl stock 78 to be cut, while the circumference of the cam member 22 is such that it makes one complete revolution to every quarter revolution of the disc 46, thus bringing the cutters 32 into cutting engagement with the pearl stock 78 and withdrawing the same therefrom after the cutting operation has been completed and again bringing the cutter 32 forwardly into cutting 70 position in time to cut the stock held in the next succeeding set of chucks 55. The range or limit of travel of the cutters 32, as determined by the cam groove 23, is further subject to adjustment by proper manipulation of the hand wheel 37 of the set screw 36 and the stud 39 carried by the underside of the upper slide 28 carrying said cutters 32. The roller 47, carried by the disc 46, revolving in a counter clockwise direction, enters and engages a radial slot 48 in the face of the chuck holder 49, (see Fig. 1) and revolves the same in a clockwise direction around the cam shaft 50, from the point A to the point B, or an arc of 90 degrees, at which latter point B the roller 47 drops out of a radial slot 48 and the chuck holder 49, as well as a chuck 55, carried thereby remain stationary until the disc 46 and the roller 47 have made three quarters of a revolution, during which time the cutters 32 are moved forward into cutting 75 engagement with and cut the pearl stock 78 in the jaws 72 of a chuck 55 which is now in the gripping, horizontal position B in the manner already described. The four radial slots 48 in the face of the chuck holders 49 80

are so arranged with respect to the four sets or rows of chucks 55 that when the chuck holder 49 is revolved from the point B to the point C, the upper perpendicular chucks 55 in the position A are moved to the horizontal position B; also a quarter of a revolution or an arc of 90 degrees, where they remain until the cutting operation is completed, the disc 46 in the meantime having completed a revolution and the roller 47 carried thereby is again ready to engage the next succeeding radial slot at the point A. It is thus seen that the cam member 22 and the disc 46 make four complete revolutions to each one revolution of the chuck holder 49. By the provision of a plurality of rows or sets of chucks 55 on the chuck holder 49, and a corresponding plurality of radial slots 48 and by properly regulating the width and circumference of the cam member 22 as well as the circumference of the disc 46, with respect to the number of chucks 55, one row of chucks 55 will be always in the vertical position A, at which point pearl stock is fed thereinto, while another row of chucks 55 is simultaneously in the horizontal position B, where the stock is cut, thus carrying on the feeding and cutting operations simultaneously without any interruption or interference and effecting a saving of time and cost. When a chuck 55 is revolved from horizontal position B, after the pearl stock has been cut, into the pendant, vertical position C, the inner end 63 of a stem 62 gradually leaves the cam surface 51 of the shaft 50, and again enters upon and bears against the raised or cylindrical surface of the shaft 50, thus forcing a chuck 55 outwardly against the force of the coil spring 66 and dislodging the tapering portions 69 from the wedge opening 70, thereby gradually loosening the grip of the jaws 72 on the said pearl stock 78. When a chuck 55 has reached the point C, said chuck is in its lowermost position, and the jaws 72 are completely open and the severed pearl stock 78 drops out by its own weight into a chute or other receptacle 90, see Fig. 5. From the pendant vertical position C, a chuck is moved into the idle horizontal position D, from which it is again moved into the vertical position A, to receive another supply of pearl stock 78 from the feed board 78', and the cycle of operations is continued.

Thus, in the three positions A, C, and D, the inner end 63 of the stem 62 bears against the raised or cylindrical surface of the shaft 50 and maintains a chuck in its outermost position against the force of the coil spring 66, and thereby maintains the jaws 72 in their loose, or non-gripping position. In the position B, however, that is, the position in which it is necessary to support the pearl stock against the pressure of the cutters 32, the inner end 63 of the chuck stem 62 bears against the

depressed or cam surface 51 of said shaft 50, thus enabling the spring 66 to draw or urge said chuck stem 62 inwardly thus tightly to wedge the tapering portions 69 of said stem into the corresponding opening 70, and thereby bringing the jaws 72 together and closing them upon the pearl stock 78, firmly to grip the same during the cutting operation. By the provision of the concaved or inwardly bent teeth 76 on the gripping jaws 72 thus substantially enclosing the pearl stock 78, see Fig. 7, and by making the spaces 77 between said teeth relatively small, the pearl stock 78, is not only firmly gripped and supported against the pressure of the cutters 32, but such stock if further backed and reinforced against such pressure, and the danger of the pearl stock giving way, or splitting along the natural lines of cleavage is entirely eliminated, thus producing parallel faced button blanks of any desired thickness the thickness of the blanks to be produced depending upon and being varied by the thickness of the spacing washers 33 intermediate said cutters 32.

I am aware of and fully conversant with U. S. Letters Patent No. 1,493,283, dated May 6, 1924, as granted to one T. G. Robinson, for process and apparatus for making button blanks from pearl stock. My present invention differs materially from and I disclaim the structure shown and described in said patent upon the following grounds:

(1) My device operates by having a fixed cam shaft about which revolves a frame carrying pearl stock.

(2) My frame operates in four sequential movements timed, to wit: from A to B; from B to C; from C to D; and from D to A, said frame movement operating intermittently from station to station.

(3) From station A to B my pearl stock is gradually gripped more firmly until station B is reached, at which time the cutting operation takes place.

(4) In moving from station B to C my pearl stock is gradually released and deposited as shown at C in Fig. 7. In my case the jaws in movement from station C to D are idle.

(5) The above operations are performed by reason of a so-called Geneva movement.

Thus, the patent to Robinson does not disclose the rotary, intermittent carriage of stock nor the Geneva movement for operating such carriage.

I desire to call especial attention to the function of the slotted guide plate 40, best seen in Figs. 1, 2, and 5, which guide plate serves the dual function of accurately aligning the cutters 32 as the same are advanced towards the pearl blanks to be cut, and in addition said guide plate serves to prevent the chips or small particles of pearl from lodging between a pair of cutters 32 and

thereby throwing the same out of their proper parallel alignment and causing breakage thereof. The guide plate 40 thus serves the dual function as above explained and is 5 an element of very great importance in the organization above described. I desire to also call attention to the manner in which the jaws 72, as seen in Figs. 9, 10, and 11, are constructed and collocated, it being apparent 10 that upon the removal of a screw 74 any jaw can be readily replaced in case of injury, and upon the removal of a pair of the screws 74, a pair of larger or smaller jaws can be substituted for those shown.

15 This feature enables my novel machine to be enabled to readily handle the pearl blanks or stock 78, as seen in Fig. 12, which may be of varying diameters for the purpose of making buttons of various thicknesses 20 and sizes. This feature of my invention is one of great importance in practice as is evident.

It will now be apparent that I have devised a novel and useful construction which 25 embodies the features of advantage enumerated as desirable in the statement of the invention and the above description and while I have in the present instance shown and described the preferred embodiment 30 thereof which has been found in practice to give satisfactory and reliable results, it is to be understood that the same is susceptible of modification in various particulars without departing from the spirit or scope of the 35 invention or sacrificing any of its advantages.

Having thus described my invention, what I claim as new and desire to secure by Letters Patent is:

40 1. A button blank dividing machine comprising a carrier, means for intermittently rotating said carrier to move work holding devices thereon and to bring them to rest successively at a plurality of stations; work holding devices comprising spindle chucks mounted radially on the carrier and means for moving them radially of the carrier and for causing them when so moved to open tangentially of the carrier as they move toward one station, to so close as they move from a station and to remain closed at the work performing station, said chucks comprising two opposed parallel jaws slotted to permit the passage of a dividing tool in 50 combination with one or more dividing tools and means to move the same radially of the carrier toward and from the work performing station.

2. A button blank dividing machine comprising a carrier, means for intermittently rotating said carrier to move work holding devices thereon and to bring them to rest successively at a plurality of stations; work holding devices comprising spindle chucks 55 mounted radially on the carrier and means

for moving them radially of the carrier and for causing them when so moved to open tangentially of the carrier as they move toward one station, to so close as they move from a station and to remain closed at the 70 work performing station, said chucks comprising two opposed parallel jaws slotted to permit the passage of a dividing tool in combination with one or more dividing tools, means to move the same radially of the carrier toward and from the work performing station, and a slotted guide plate for said dividing tools positioned between said tools and carrier.

3. A button blank dividing machine comprising a carrier, means for intermittently rotating said carrier to move work holding devices thereon and to bring them to rest successively at a plurality of stations; work holding devices comprising spindle chucks 80 mounted radially on the carrier and means for moving them radially of the carrier and for causing them when so moved to open tangentially of the carrier as they move toward one station, to so close as they move 85 from a station and to remain closed at the work performing station, said chucks comprising two opposed tensioned parallel jaws slotted to permit the passage of a dividing tool in combination with one or more dividing tools, means to move the same radially of the carrier toward and from the work performing station, and a slotted guide plate for the dividing tools positioned between 90 said tools and carrier.
